UNITED STATES PATENT OFFICE.

ROBERT F. PAINTER, OF GREENFIELD, MASSACHUSETTS, ASSIGNOR TO THE WARNER MANUFACTURING COMPANY, OF SAME PLACE.

CANOPY-HOLDER.

SPECIFICATION forming part of Letters Patent No. 424,572, dated April 1, 1890.

Application filed November 25, 1889. Serial No. 331,537. (No model.)

To all whom it may concern:

Be it known that I, ROBERT F. PAINTER, a citizen of the United States, residing at Greenfield, in the county of Franklin and State of Massachusetts, have invented certain new and useful Improvements in Canopy-Holders, of which the following is a specification.

My invention relates to canopy-holders, and has reference more particularly to that class 10 of devices in which a divided hollow sphere or ball is mounted in a divided holder or support, a single clamping device being used to clamp the two parts of the sphere upon the canopy-rod and the holder or support upon 15 the sphere.

In the drawings, Figure 1 is a perspective view of my improved holder; Fig. 2, a horizontal sectional view; Fig. 3, a vertical sectional view from front to rear on the line xx , Fig. 2; 20 Fig. 4, a vertical sectional view on the line yy , Fig. 2; and Fig. 5, a perspective view of the parts separated.

The holder comprises a horizontally-disposed band or ring A and suitable attaching- 25 arms B, which latter are cast integral with that part of the ring to be secured to the vehicle. The ring or band is divided transversely at its middle to form two clamping-sections a and b , whose inner faces conform 30 to the outer face of the divided sphere or ball C, carrying the rod D. The section a , to which the attaching-arms are secured, is provided with teats c to engage corresponding sockets or depressions d in the section b at their point 35 of meeting, in order to assist in maintaining the two sections of the ring or band in the same horizontal plane, the section b being also provided with a short tubular neck or extension e axially in line with the band.

40 The divided sphere or ball C is hollow and is made up of two semi-spherical sections f and g , which are duplicates of each other, the two sections being each provided on their meeting edges with semicircular notches h to receive and seat the rod D. Each section f and g is further provided with an elongated slot i , through which passes the bolt or stem E, forming a part of the clamping devices, and with a teat j and socket or depression k , which 45 serve to keep the two sections in such position that the notch h of one section shall be

opposite the corresponding notch of the other section. Bolt E is provided with a T-shaped head l , which bears against the outer face of ring-section a , and with a stem m , which 55 passes freely through the tubular extension or neck e of ring-section b , the said stem being threaded outside of or beyond the neck to receive a thumb-nut F. It will be noted that the bolt E passes around the canopy-rod 60 D, and in order to permit the insertion of the bolt through the ring-section a the latter is made with an opening or slot n in its rear face.

With the parts thus constructed and arranged it will be seen that by loosening the 65 thumb-screw the parts a b of the band or ring are released, as are also the parts f g of the ball. After the rod D is inserted the thumb-screw is turned, so as to tighten or draw the 70 two parts of the band or ring together upon the sphere or ball, this action also forcing the two parts of the sphere or ball together upon the rod, thereby effectually clamping not only the rod in the sphere, but also clamping the 75 sphere in position. The sphere or ball projects above and below the band or ring, thereby permitting the rod carried by the ball to be given any desired inclination backward or forward, sidewise, or in any intermediate direction, the slots i in the ball-sections 80 allowing of this freedom of motion when the thumb-screw is released. It will also be noted that the rod D is capable of a vertical adjustment relatively to or through the ball or sphere independently of its inclination. 85

By making the two ball-sections duplicates of each other the cost of the fixture is materially lessened.

No broad claim is made herein to a divided sphere nor to a divided support, as these features are not broadly new. I believe, however, that the device herein described and shown is much better than those now in use, is lighter, is cheaper to make, as the parts require no extensive finishing, and is found to 90 work well.

In Fig. 2 the bolt E is shown as provided with an opening to receive the canopy-rod D; but this is not essential, it being clear that the bolt need be offset to pass only on one 100 side of the rod, this change being indicated by the dotted lines in said figure. A nut G

is applied to the end of the bolt E to prevent the thumb-nut from working off.

Having thus described my invention, what I claim is—

5. 1. In combination with a divided ring or band, a divided ball and a clamping device, all substantially as shown and described.

10. 2. In combination with a divided ball adapted to receive a canopy-rod, a divided ring or band adapted to receive the ball and a clamping device serving to bind the parts of the ball upon the rod and the ring or band upon the ball.

15. 3. In combination with a divided ring or band and a divided ball, a bolt passing through the ball and ring and serving to clamp the parts together.

20. 4. In combination with band-sections a and b, the former having a slot n, ball-sections f and g, each provided with a slot i, a bolt E,

passing through the slots n and i and provided with a head l, and a nut F, applied to the threaded end of the bolt.

25. 5. In combination with a divided supported ring or band and a clamping device, the ball or sphere comprising two parts f and g, each of said parts f g being provided with a seat j, sockets h and k, and a slot i.

30. 6. In combination with a divided ball or sphere and a clamping device, a divided ring or band comprising two sections a and b, one of said sections being provided with a seat c and the other with socket d.

In witness whereof I hereunto set my hand in the presence of two witnesses.

ROBERT F. PAINTER.
